UNITED STATES PATENT OFFICE.

MILLIE SANDERS, OF OAKLAND, CALIFORNIA.

TONIC AND DRESSING FOR THE HUMAN HAIR.

1,368,758.

Specification of Letters Patent. Patented Feb. 15, 1921.

No Drawing.

Application filed August 20, 1920. Serial No. 404,763.

To all whom it may concern:

Be it known that I, MILLIE SANDERS, a citizen of the United States, residing at 951 Thirty-sixth street, in the city of Oakland, in the county of Alameda and State of California, have invented a new and useful Composition of Matter to be Used as a Tonic and Dressing for the Human Hair, of which the following is a specification.

10 The object of the invention is to promote the growth and improve the quality and appearance of the hair and in a simple, practical and thoroughly effective manner so to treat kinky or curly human hair as to cause 15 it to become temporarily straight and to retain this condition through any period of time while the compound is used at regular intervals.

My composition consists of the following 20 ingredients combined in the proportions stated; viz:

White vaseline	2 pounds.
Oil of cinnamon	1 teaspoonful.
Oil of bergamot	1 teaspoonful.
25 Quinin	1½ teaspoonsful.
Sulfur	1 teaspoonful.
Oil of lilacin	½ teaspoonful.

These ingredients are to be thoroughly 30 mixed together by agitation and submitted to heat until the mass is reduced to the consistency of paste. When cool it is ready for use.

In using the above-named composition a

small quantity of the same should be rubbed 35 thoroughly into the scalp every other day, with the tips of the fingers, and a small quantity then applied to the hair.

By the use of the above composition the hair will be stimulated to growth, will be 40 strengthened and invigorated and upon being brushed thoroughly with an ordinary hair brush, after applying the composition as above directed, will appear straight with a fine and glossy appearance. I am aware 45 that some of the ingredients have been used for the same purpose, but I am not aware that all the ingredients of my composition have been used together.

What I claim and desire to secure by Letters Patent of the United States is:

1. The herein described composition of matter consisting of white vaseline, oil of cinnamon, oil of bergamot, quinin, sulfur and oil of lilacin, substantially as described 55 and for the purpose specified.

2. The herein described composition of matter for use as a tonic and as a dressing for the human hair consisting of white vaseline two pounds, oil of cinnamon one tea- 60 spoonful, oil of bergamot one teaspoonful, quinin one and one-half teaspoonsful, sulfur one teaspoonful and oil of lilacin one-half teaspoonful, substantially as described.

MILLIE SANDERS.
